(57) **CLAIM**

The ornamental design for an interactive robotic apparatus, as shown and described.

DESCRIPTION

FIG. 1 is a front elevation view of an ornamental design for an interactive robotic apparatus;

FIG. 2 is a right side view thereof;

FIG. 3 is a left side view thereof;

FIG. 4 is a back view thereof;

FIG. 5 is a top plan view thereof;

FIG. 6 is a bottom view thereof; and,

FIG. 7 is a perspective view thereof.

The broken lines in FIGS. 1-7 are for illustrative purposes only and form no part of the design.
